US00D631926S

(12) **United States Design Patent**
Arzente et al.

(10) **Patent No.:** US D631,926 S
(45) **Date of Patent:** ** Feb. 1, 2011

(54) **WATER SPORTS BOARD**

(75) Inventors: **George Arzente**, Laguna Beach, CA (US); **Brian Peterson**, Oceanside, CA (US)

(73) Assignee: **Catch Surfboard Co.**, San Clemente, CA (US)

(**) Term: **14 Years**

(21) Appl. No.: **29/355,362**

(22) Filed: **Feb. 5, 2010**

(51) **LOC (9) Cl.** 21-02

(52) **U.S. Cl.** D21/769

(58) **Field of Classification Search** D21/769-770, D21/801, 803, 809; 114/253, 345-346; 441/35, 441/66, 40-42, 129-132; 472/128-129; D12/5, 6, 316

See application file for complete search history.

CLAIM

The ornamental designs for a water sports board, as shown and described.

DESCRIPTION

FIG. 1 is a top perspective view of an embodiment of a water sports board according to the present designs;

FIG. 2 is a bottom perspective view of the embodiment of FIG. 1;

FIG. 3 is a top-plan view of the embodiment of FIG. 1;

FIG. 4 is a bottom-plan view of the embodiment of FIG. 1;

FIG. 5 is a right-side elevational view of the embodiment of FIG. 1;

FIG. 6 is a front elevational view of the embodiment of FIG. 1;

FIG. 7 is a rear elevational view of the embodiment of FIG. 1;

FIG. 8 is a cross-sectional view of FIG. 3 taken through line 8—8 of the embodiment of FIG. 1; and,

FIG. 9 is a cross-sectional view of FIG. 3 taken through line 9—9 of the embodiment of FIG. 1.

The broken lines in the drawing are for illustrative purposes and form no part of the claimed design.
